UNITED STATES PATENT OFFICE.

WILLARD HARRIS NORRIS, OF GLEN'S FALLS, NEW YORK.

BOSOM-SHIRT.

SPECIFICATION forming part of Letters Patent No. 289,778, dated December 4, 1883.
Application filed June 5, 1883. (No model.)

To all whom it may concern:

Be it known that I, WILLARD HARRIS NORRIS, of the village of Glen's Falls, county of Warren, and State of New York, have invented a new and useful Improvement in Bosom-Shirts, of which the following is a specification.

My invention relates to apparel-shirts and a manner of attaching the bosoms thereto; and 10 my invention consists, as will be subsequently described herein, in the combination, with the exterior front facing or front re-enforce of a shirt, of a bosom attached to said facing throughout the length of the bosom, on the 15 plait-lines thereof, between the collar-band and the lower end of the bosom, and with the body proper of the shirt free from and unattached to the bosom and exterior facing or re-enforce between the neckband and the bottom 20 union of the bosom, re-enforce, and body proper of the shirt, the object and purpose of my invention being to so make the shirt that the bosom will have a free lateral adjustment to the motion of the arms and body, and 25 vertically be held in place when being worn.

In the accompanying drawings, forming a part of this specification, there are two figures shown illustrating my invention, and in both of which the same designation of parts by letter reference is used.

Figure 1 shows a front view of that part of a shirt which contains the bosom, front exterior facing or re-enforce, and shirt-body proper at the front, with portions of the re-enforce shown as cut out at the upper corners. 35 Fig. 2 illustrates, in a cross-section taken on the line *x* *x* of Fig. 1, the relative position of the parts, with their thickness somewhat exaggerated to better illustrate them.

40 The parts of the shirt thus shown and the seams which unite them are designated by letter reference, and as follows:

The letter *B* indicates the bosom, *b b* the sides of the latter, *P* its longitudinal central 45 plait, and *p p* seams connecting the bosom with the re-enforce or front facing, *R*.

The letter *S* designates the shirt-body proper, and *N'* indicates stitching connecting the re-enforce with the shirt-body, *N²* where this

stitching in continuity unites the bosom and 50 re-enforce to the shirt-body at the bottom of the bosom, and *N²* where these same parts are united at the neckband.

Thus made, the sides of the bosom (designated at *b b*) are left free for adjustment, and 55 the body of the shirt back of the re-enforce is unattached to the latter between the top and bottom of the bosom. While the sides of the bosom are thus left free for lateral adjustment, the bosom and attached re-enforce are also 60 left free for lateral adjustment independently of the shirt-body proper at the front, between the neckband and the bottom of the bosom.

I am well aware that I cannot claim, broadly, a fly-edge upon the bosom, and that my 65 invention as relating thereto is limited to my improved method of producing one, in combination with a re-enforce that is unattached to the shirt-body proper at the front, between the neckband and the bottom of the bosom. 70

Having thus described my invention, what 70 I claim, and desire to secure by Letters Patent, is—

1. In a shirt, the combination, with a front exterior facing or re-enforce, of a bosom attached on its plait-line centrally to the said re-enforce or front facing, and said re-enforce or facing and attached bosom joined to the shirt-body at the bottom and neckband top of the bosom, with the sides of said bosom unattached, as shown and described. 75

2. In a shirt, the combination, with an exterior facing or re-enforce, of a bosom attached longitudinally and centrally on its plait-line to said re-enforce or exterior facing, with the 85 latter and connected bosom attached to the shirt-body at the bottom and neckband top of the bosom, with the shirt-body unattached to said re-enforce or exterior facing between the neckband top and the bottom of the 90 bosom, as shown and described.

Signed at Glen's Falls, New York, this 1st day of June, 1883, and in the presence of the two witnesses whose names are hereto attached.

WILLARD HARRIS NORRIS.
